TOY VEHICLE

Walter Majewski, Chicago, Ill., assignor to Lake-
wood Mfg. Co., Chicago, Ill., a corporation of
Illinois

Application December 18, 1936, Serial No. 116,542

3 Claims. (Cl. 280—87.03)

This invention relates in general to toy vehicles, and more particularly to a toy vehicle which is adapted to be propelled by bouncing movement of the operator thereon.

5 A principal object of the invention is the provision of a toy vehicle, having a spring supported seat, which will be automatically impelled forwardly a given distance upon each reciprocating movement imparted to the seat by the operator.

10 Another important object of the invention is the provision of a novel rear wheel assemblage and means for suspending the same which make such movement of the vehicle possible by preventing rotation of the rear wheels upon downward movement of the seat and permitting rotation thereof upon upward movement of the seat.

15 A further important object of the invention is the provision of a toy vehicle which simulates the action of riding a horse, while being so safe in operation as to be adapted for use by very young children.

20 Another important object of the invention is the provision of such a toy vehicle which may be easily and cheaply manufactured, while being of such sturdy and durable construction as to withstand the hard use to which it will be subjected by children.

25 Numerous other objects and advantages of the invention will be apparent as it is better understood from the following description, which, when taken in connection with the accompanying drawing, discloses a preferred embodiment thereof.

In the drawing,

30 Figure 1 is an elevational view of a toy vehicle embodying the features of the invention;

Fig. 2 is a top plan view of the device of Fig. 1; and

Fig. 3 is a sectional view taken substantially 40 on line 3—3 in Fig. 2.

45 Referring more particularly to the drawing, reference numeral 11 indicates a frame member of any suitable material which has mounted upon it a seat 12 which may be adjustable relative thereto if desired. Extending upwardly from the seat 12 is a flat member 13 which may be cut in any suitable shape, such as that of a horse's head. A bar 14 is mounted at right angles to the member 13 and extends therethrough so that a grip means is afforded the operator when using the device. Pivottally mounted on the frame member 11 at 15, is a foot rest 16 adapted for steering the vehicle.

50 Pivotally secured to the foot rest 16 by bolts 17, or the like, are a pair of forwardly extending

bars or rods 18, which in turn are pivotally secured at their forward ends to a cross member 19 which is pivotally mounted at 21 on the frame member 11. A pair of wheels 22 are rotatably mounted upon the cross member 19. The assemblage comprising the foot rest 16, arms 18, cross member 19 and wheels 22, constitutes steering apparatus for the toy vehicle.

5 A heavy gauge steel spring 23 is inserted between the cross member 19 and the frame member 11, and is held in contacting relationship with the frame member 11 adjacent its forward end by means of a U-shaped bracket 24. A cross member 25 is rigidly secured to the spring 23 at its rear end by means of a bolt 26, or the like. Secured to the rear surface of the cross member 25 is a U-shaped supporting member 27 having a slot 28 formed in each of the downwardly extending arms 29 thereof. A rod 31 extends through the slots 28 of the arms 29 so as to be freely rotatable therein and slidable longitudinally of the slots, and is provided with a wheel 32 mounted on each end thereof.

10 In the use of the toy vehicle, the operator seats himself upon the seat 12, grasps the rod 31, and places his feet on the foot rest 16. Upon bouncing downwardly the frame member 11 is moved from the full line position to the dotted line position shown in Fig. 1. As can be seen from this figure, the shape of the lower surface of the frame member 11 and the shape of the spring 23 are such that the above described downward movement of the frame member 11, which will be about the center of the wheels 22 as a pivot point, will cause a downward flexing of the spring 23 to its dotted line position, as shown in Fig. 1. This is due to the fact that a bending moment is applied to the spring by the frame member 11, which is assured by the shape of these members and the retaining bracket 24 holding the forward part of the spring in contact with the lower surface of the frame member. The initial flexing movement of the spring 23, as above described, results in the frame member 25 being pressed downwardly into contact with the outer periphery of the rear wheels 32. Such relative movement between the member 25 and the wheels 32 is permitted by the slots 28 in the supporting member 27, and results in a positive braking of the rear wheels to prevent any movement thereof relative to the floor or other supporting surface. Consequently, further flexing of the spring 23 results in forward movement being imparted to the forward wheels 22, as illustrated in broken lines in Fig. 1.

The subsequent return or upward movement of the frame member 11, which is induced in part by the reactive force of the spring 23, results immediately in the rear frame member 25 being moved forwardly out of contact with the rear wheels 32 to permit rotation thereof, so that the vehicle as a whole will roll forwardly under the impetus of the reactive force of the spring 23 in its return to the full line position of Fig. 1. It will thus be apparent that the vehicle will be automatically impelled forwardly a given distance upon each reciprocating or bouncing movement imparted to the seat 12 and frame member 11 by the operator.

15 The above described toy vehicle may be easily and cheaply manufactured, since the members 11 to 14, 19 and 25 may be constructed of wood, if desired, and the members 16, 18, 24 and 27 may be readily formed from strap iron, or the like.

20 In the embodiment of the device shown in the drawing, the rear frame member 25 is disclosed as extending laterally beyond the wheels 32 so as to insure the above described braking action thereof on the wheels. If it is desired, the frame member 25 may be dispensed with, and the bracket member 27 secured directly to the rear end of the spring 23 with its downwardly extending arms 29 made sufficiently long to permit the wheels 32 being mounted in an inner position relative thereto. With this construction, the transverse portion of the bracket 27 will contact the outer surface of the wheels 32 in the initial part of the extending movement imparted to the spring 23 to brake the rear wheels in the same manner as described above relative to the frame member 25.

25 It is thought that the invention and many of its attendant advantages will be understood from the foregoing description, and it will be apparent

30 that various changes may be made in the form, construction and arrangement of the parts without departing from the spirit and scope of the invention or sacrificing all of its material advantages, the form hereinbefore described being merely a preferred embodiment thereof.

I claim:

1. A toy vehicle, comprising a spring member, a rigid frame member secured to said spring member at one end thereof, a seat mounted on said frame member, and wheels suspended from said spring member at the other end thereof and from said frame member adjacent its point of connection to said spring member, whereby the vehicle is adapted to be propelled by bouncing movements of the operator on said seat.

2. A toy vehicle, comprising a spring member, a rigid frame member secured at one end to the forward part of said spring member, a seat mounted on the other end of said frame member, a pair of freely rotatable wheels mounted adjacent the forward end of said members, and a pair of wheels suspended from the rear end of said spring member for longitudinal movement relative thereto, whereby downward movement of said seat will move said spring member relative to said rear wheels to prevent rotation thereof and upward movement of said seat will allow said spring member to move relative to said rear wheels to permit rotation thereof.

3. In a toy vehicle having a seat and adapted to be propelled by bouncing movement of the operator on said seat, a spring adapted to be extended by the downward movements of said seat, and a pair of normally freely rotatable wheels suspended from said spring and adapted to be held against rotation by said spring during such extension of said spring.

WALTER MAJEWSKI.
